TICKET ISSUING MACHINE

Herman Soltz, Woodside, N. Y., assignor to General Register Corporation, New York, N. Y., a corporation of Pennsylvania

Application September 30, 1935, Serial No. 42,773

8 Claims. (Cl. 271—2.4)

This invention relates to a ticket issuing machine and particularly to the type of machine adapted for theatre use for issuance of one or more tickets in a single operation.

It is the broad object of the present invention to provide a ticket issuing machine which is simple in construction and silent in operation. In most machines heretofore in use, the depression of a key or actuation of other tripping mechanism has involved the snapping of a certain element or plurality of elements to limited positions under the action of a spring, producing a comparatively loud and annoying sound and causing substantial shock to the mechanical parts by reason of the impact. Furthermore, during the operation of most such machines, there has been involved clashing of elements which, in view of the high speed of operation, produced considerable noise and shock. The machine forming the subject matter of the present invention is so designed as to eliminate substantially all sharp engagements of elements so that the resulting machine is remarkably quiet in operation.

Another object of the present invention is the provision of means of improved character for determining the issuance of one or some particular number of tickets as determined by a depressed key.

Other objects of the invention, relating more particularly to details of construction, applicable not only to multiple ticket issuing machines but also to single ticket issuing machines, such as, for example, restaurant check machines, will be apparent from the following description read in conjunction with the accompanying drawings, in which:

Fig. 1 is a vertical section taken longitudinally of the apparatus and showing substantially the parts as they would appear if the right-hand side plate were removed;

Fig. 2 is a similar vertical section but taken on a plane to the left of that of Fig. 1 so as to show elements located adjacent the left-hand side plate;

Fig. 3 is a horizontal section looking upward taken on a plane indicated at 3—3 in Fig. 1;

Fig. 4 is a horizontal section also looking upward taken as indicated at 4—4 in Fig. 1;

Fig. 5 is a vertical section taken on the plane indicated at 5—5 in Fig. 1;

Fig. 6 is a vertical section taken on the plane indicated at 6—6 in Fig. 1; and

Fig. 7 is a fragmentary sectional view on an enlarged scale showing certain of the driving

parts in elevation as they would appear with others removed.

The present machine is so designed that a plurality of ticket issuing units may be assembled within an outer casing side by side so as to deliver different kinds of tickets through a common top plate of the outer casing and so as to be driven from a single motor through a common shaft extending transversely below the several units. Such arrangement is at present common in machines of this type and is particularly convenient since individual units containing the major portion of the mechanism may be removed and replaced by other identical ones if necessity for repair arises. Sufficient units, which are placed side by side, may be retained in proper relationship to each other either by suitable construction of the outer housing or by means of transverse members engaging the individual units and holding them in proper relative positions. Since this application is concerned only with the mechanism in a single unit, there is disclosed only one such unit, there being additionally shown in Figs. 1 and 6 the countershaft 14 which forms the common drive for a plurality of units from a single motor, which motor is adapted to be started upon the depression of any key of any unit.

Each of the units comprises suitable plates indicated at 2 properly spaced from each other by transverse members, there being additionally provided for the support of parts of the mechanism other members such as the plate 3. Operation of the machine is effected through the depression of one of keys 4 passing through suitable slots in a spacer plate 5 and individually pivoted at their lower ends to key levers 6 mounted upon a transverse pin 8 and held in properly spaced relative relationship by means of spacers on the pin and slotted combs 16 and 18. Each of the levers 6 is provided with a nose 10 which yieldingly cooperates with either the upper or under surface of an inward projection of a spring strip 14 so that each lever is yieldingly maintained in either an upper or lower position. The spring strips 14 may be provided as individual teeth on a single member secured to the comb 16.

Each of the key levers 6 is provided with a shoulder 20, the function of which will be brought out later. In the form of the invention illustrated, these shoulders 20 are lined up with each other transversely of the unit. Pivoted on the pin 8 and extending transversely below all of the key levers 6 is a stirrup 22 to which is secured a depending arm 24 adapted to close a switch by engagement of a transverse plate of 55

well known type. This plate extends transversely of all of a plurality of units so as to be moved to close a single switch upon depression of a key and consequent movement of the stirrup of any one of the units.

The stirrup 22 is also provided with a rearwardly extending arm 26 which, at its rear end, is turned as indicated at 28 so as to cooperate with the lower end of a lever 30, which is pivoted at 32, provided with an end for manual manipulation, indicated at 34. When the lever 30 is in the position illustrated in Fig. 2, the stirrup 22 may be rocked by depression of a key. On the other hand, if the lever is moved in a clockwise direction as viewed in Fig. 2 until its lower end overlies the turned end 28, it will be impossible to depress any of the keys and consequently the unit will be rendered inoperative. Locking of a unit is thus provided since normally the housing is provided with a locked top plate beneath which the upper end 34 of the lever 30 is located. When a plurality of units are provided, therefore, it is possible for the person having custody of the key of the machine to lock 25 certain of the units so that they may not be operated to issue tickets.

Pivoted at 36 to the extension 26 is a link 38, the upper portion of which is notched, as indicated at 40, in such fashion that either of the notches may engage a pin 42 under the action of a spring 44, with the result that the link 38, and consequently the stirrup, is yieldingly held in an upper or lower position. The spring 44 is so arranged that upon the application of longitudinal force in either direction the link 38 may be moved from one alternative position to the other.

The lower end of the link 38 is notched at 46 to engage a forwardly projecting arm of a plate 48 pivoted at 50 and 52 in the side plates of the frame, as shown in Fig. 4. The plate 48 is provided with a wedge-shaped rearward extension 54 which, when the machine is stationary, is engaged with an ear 56 carried by a plate 58 pivoted to a disc 64 as indicated at 66 and urged away from said disc by a leaf spring 62. The disc 64 is secured to a gear 66 and through this gear drives other portions of the mechanism. When the ear 56 is engaged, as just indicated, 50 by the wedge 54, it is held axially out of the path of pins 68 carried by a gear 70 which is arranged to mesh with a pinion 72 carried by the motor-driven countershaft 74, there being provided one or more pinions 72 corresponding 55 to the number of units located side by side in the machine. When the motor is operated, it drives, through suitable reduction gearing, the shaft 74, and consequently the gear 70 and pins 68 of all of the units. However, unless operation of a 60 particular unit is predetermined by depression of a key thereof, the rotation of the pins 68 is ineffective to produce issuance of a ticket from that unit, since the ear 56, under such conditions, will not be engaged. On the other hand, 65 when operation is predetermined, the ear 56 will be disengaged by its wedge 54 in position to be driven by one of pins 68 so that a direct drive between gear 70 and gear 66 is provided. By the provision of a plurality of pins 68, it will be clear 70 that the clutch is engaged quite soon after the actuation of the motor operation, so that the impact occurring at this point is slight, and though rapid operation is effected, there is no substantial noise.

The gear 66 meshes with a gear 76 which car-

ries a crank pin 78, to which is pivoted a link 80, the forward end of which is pivotally connected to a lever 82 fulcrumed at 84 upon an upstanding ear of a slide 86 guided for movement in slots 88 in the side plates. The slide 86, as most clearly shown in Fig. 3, is provided with a series of steps 90 in its forward edge which are lined up with and adapted to engage the corresponding shoulders 20 on the key levers to produce variable operation of the ticket issuing mechanism as hereafter described.

The upper end of lever 82 is pivoted to a rack 92, the teeth 94 of which mesh with a pinion 96 formed on a sleeve to which is secured a ratchet 98 with the teeth of which cooperates a pawl 100 urged into engagement therewith by a spring 102, the pawl being pivoted upon, and the spring being secured to, a pinwheel 104 carrying a series of pins 106 designed to engage perforations in a ticket strip. The ticket strip is led to the pinwheel between guide members 108 and 110 pivoted to the side plates at 112 and 114, respectively, and arranged so as to be simultaneously movable away from the pinwheel by reason of an ear 116 secured to guide 110 and having an inner turned end engaging guide 108, so that as guide 110 is pulled forwardly, guide 108 is also moved against the tension of spring 118 to clear the pins and thus afford easy feed for the ticket strip. Inward movement of both 30 of the guides is limited by engagement of an upturned finger 120 with the fixed knife 122 of the cutting arrangement, the finger 120 extending above the knife 122 so as to be manually engageable to move the guides forwardly. The 35 guiding passage is continued by a portion 124 secured to one of the side plates. Cooperating with the fixed knife 122 there is a movable knife 126 held downward so as to tightly engage the fixed knife 122 by means of a cover guiding plate 40 128. With this plate and the knife there engages a member 130 pivoted to the upper end of a knife operating lever 136 and pulled downwardly through a link 132 and spring 134. The 45 knife operating lever 136 is provided with a follower roller 140 engaging within a cam groove 142 formed in a disc 64.

The pinwheel 104 carries a plurality of axially extending pins 144 corresponding in number to the pins 106 and bearing a proper angular relationship thereto. These pins 144 are arranged to engage at proper times the upper end of a lever 146 pivoted upon a transverse pin 148 and urged in a counterclockwise direction, as viewed in Figs. 1 and 7, by a spring 150. The lever 146 is provided with a second arm 152 which acts as a cam follower to be acted upon by rollers 154 and 156 carried by the gear 76. The rollers 154 and 156 serve to move the lever 146 out of the path of the pins 144. Normal clockwise movement of 60 the pinwheel 104 is prevented by the location of the lever 146 in the position of Fig. 7.

A bell crank 158 pivoted at 160 and urged in a clockwise direction, as viewed in Fig. 2, by means of a spring 162, is adapted to be acted upon 65 at the end of each cycle by a roller 164 carried by the gear 66. When so acted upon, its edge 166 engages and depresses the forwardly projecting portion of plate 48 with the resultant imparting of a clockwise movement to the stirrup 22 and opening of the switch, and restoration of the depressed key lever 6 to its initial raised position. There is secured to the pinwheel 104 a pinion 168 which, through suitable intermediate gearing 170, 75

drives a counter 172 to indicate the number of tickets issued.

The operation of the machine will be clearly apparent from the above description of its construction. Upon depression of one of the keys 4, the corresponding key lever 6 is moved downwardly, producing a closure of the motor switch through 24 and engagement of the clutch by the liberation of the ear 56, so that it is brought into the path of one of the pins 68. By reason of the provision of the lower depression 40 in the link 38, the stirrup 22 is held in the position to which it has been moved by the key, and the switch is held closed during the ensuing cycle. Likewise, the wedge 54 is held out of the path of the ear 56.

The rotation of gear 66 takes place in a clockwise direction, as indicated by the arrow in Fig. 2. As the cycle begins, the link 80, which was in substantially a rearward dead center position, will move forwardly, thereby acting upon the lever 82. The arrangement is such that the resistance to movement of the pinion 96 and its connected parts is greater than the resistance to movement of the slide 86, so that, as a consequence, the slide 25 86 is forced forwardly, the left-hand end of link 92 forming a substantially fixed fulcrum for the lever 82. This forward movement of the slide 86 may continue until the step 90, corresponding to the depressed key lever, engages the shoulder 30 20 of that lever, whereupon, since the slide may no longer move forwardly but is positively arrested, the continued forward movement of link 80 produces rearward movement of the rack 92 and rotation of pinion 96. It will thus be seen that 35 the throw of the crank pin 78 gives rise to two distinct mechanical operations, the first involving the movement of slide 86 to a limiting position, and the second the rotation of the pinion 96. The relative values of these movements obviously depend upon the free movement of the 40 slide 86 to its limited position determined in turn by the heights of the steps 90. By suitable location of the steps, therefore, it is possible to provide variable movements of the pinion 96, sufficient, in the present machine, to issue one to five 45 tickets as predetermined by the depressed key. It may be noted that the engagement between a step 90 and shoulder 20 is not produced by any spring but by a relatively slow movement of the 50 slide 86, so that noise is very substantially minimized. During the forward movement of the link 80 and consequent variable rotation of the pinion 96, the pinwheel 104 is driven through the ratchet and pawl arrangement 98 and 100, the ticket strip is fed forwardly and the predetermined 55 number of tickets moved past the line of severance of the knives.

As the link 80 takes its rearward stroke, the rack 92 may be moved forwardly until the lever 60 82 engages the pin 83, whereupon the slide 86 is moved rearwardly to its initial position, stoppage of the machine taking place when the link 80 reaches the position in Fig. 2. During this reverse movement of the rack 92, the ratchet 98 moves idly from beneath the pawl 100.

The above describes the variable operation of the pinwheel. Before the pinwheel moves, however, it must be released by the lever 146, this being effected, as indicated above, by engagement 70 of the rollers 154 and 156 with the cam following extension 152 of this lever. After the completion of the feeding stroke of the pinwheel, the rollers 154 and 156 release the lever 146, bringing it into the path of the next succeeding pin 144 to prevent overrun of the pinwheel.

After the feed of the ticket strip takes place, the cam 142 acts upon the knife operating lever 136, giving the knife a forward stroke to sever the ticket strip and then a rearward stroke to open up a space for the passage of the ticket strip in the next cycle.

As the gear 66 nears the end of a rotation, the pin or roller 164 which it carries engages the bell crank 158, causing the edge 166 to move the plate 48, opening the switch, restoring the depressed key lever to its initial position and also bringing the wedge 54 into the path of the ear 56. Consequently, as the ear 56 comes round, driven by a pin 68, it will be disengaged from its driving pin and arrested in its initial position, 15 the wedge insuring a cushioned stoppage for the rotating clutch elements and the parts which they drive. The gear 70 and pin 68, however, may continue to spin with the overrun of the motor. No attempt is made to sharply arrest the 20 motor and, as a result, no noise occurs from this source.

During the issue of the ticket, it will be obvious that the counter is advanced to correspond with 25 the number of tickets issued.

The pinwheel is normally prevented from rotating in either direction. Forward movement is prevented, as indicated above, by the lever 146. Reverse movement is prevented since, in order to partake of any substantial movement in such 30 direction, it would be necessary for the pinwheel to drive the pinion 96 and hence the rack. The rack, however, cannot move because of the restraint upon lever 82 imposed by the pin 83 and the dead center location of the crank 78. It is 35 thus impossible for tickets to be drawn out of the machine except as predetermined by key operation and for disengagement of a ticket strip by the pinwheel to occur.

It will be clear that numerous variations may be 40 made in the specific embodiment of the invention without departing from the scope as defined in the following claims.

What I claim and desire to protect by Letters Patent is:

1. A ticket issuing machine comprising means for delivering one or more tickets in a cycle of operation, a plurality of keys, a member mounted for movement in a fixed path, a lever pivoted intermediate its ends on said member, means for imparting to one end of the lever a substantially constant forward and backward stroke in every cycle of operation, key controlled means for variably limiting the movements of said member depending upon the number of tickets to be issued, and connections between the other end of the lever and the delivering means.

2. A ticket issuing machine comprising means for delivering one or more tickets in a cycle of operation, a plurality of keys, a slide, a lever pivoted intermediate its ends on said slide, means for imparting to one end of the lever a substantially constant forward and backward stroke in every cycle of operation, key controlled means for variably limiting the movements of said slide depending upon the number of tickets to be issued, and connections between the other end of the lever and the delivering means.

3. A ticket issuing machine comprising means for delivering one or more tickets in a cycle of 70 operation, a plurality of keys, a member mounted for movement in a fixed path, a lever pivoted on said member, single revolution mechanism for imparting to one end of the lever a single substantially constant forward and backward stroke 75

in every cycle of operation, key controlled means for variably limiting the movements of said member depending upon the number of tickets to be issued, and connections between the other end 5 of the lever and the delivery means.

4. A ticket issuing machine comprising means for delivering one or more tickets in a cycle of operation, a plurality of keys, a member mounted for movement in a fixed path, a lever pivoted on 10 said member, single revolution mechanism, including a clutch and means for disengaging the clutch after a single revolution for imparting to one end of the lever a single substantially constant forward and backward stroke in every 15 cycle of operation, key controlled means for variably limiting the movements of said member depending upon the number of tickets to be issued, and connections between the other end of the lever and the delivery means.

5. A ticket issuing machine comprising means for delivering one or more tickets in a cycle of operation, a plurality of keys, a slide, a lever pivoted on said slide, single revolution mechanism for imparting to one end of the lever a single 25 substantially constant forward and backward stroke in every cycle of operation, key controlled means for variably limiting the movements of said slide depending upon the number of tickets to be issued, and connections between the other 30 end of the lever and the delivery means.

6. A ticket issuing machine comprising means for delivering one or more tickets in a cycle of operation, a plurality of keys, means for yieldingly holding actuated keys in the positions to 35 which they are moved, a member mounted for movement in a fixed path, a lever pivoted on said member, single revolution mechanism, including a clutch and means for disengaging the clutch

after a single revolution and for positively restoring actuated keys to normal position, for imparting to one end of the lever a single substantially constant forward and backward stroke in every cycle of operation, key controlled means for variably limiting the movements of said member depending upon the number of tickets to be issued, and connections between the other end of the lever and the delivery means. 5

7. A ticket issuing machine comprising means 10 for delivering one or more tickets in a cycle of operation, a plurality of keys, a member mounted for movement in a fixed path, a lever pivoted on said member, means for imparting to one end of the lever a substantially constant forward and 15 backward stroke in every cycle of operation, key controlled means for variably limiting the movements of said member depending upon the number of tickets to be issued, connections between the other end of the lever and the delivery means, 20 means normally preventing movement of the delivery means, and means for rendering the last named means inoperative during the cycle when delivery is to take place.

8. A ticket issuing machine comprising means 25 for delivering at least one ticket in a cycle of operation, a member mounted for movement in a fixed path, a lever pivoted on said member, means for imparting to one end of the lever a forward and backward stroke in every cycle of 30 operation, means for limiting the movements of said member, connections between the other end of the lever and the delivery means, means normally preventing movement of the delivery means, and means for rendering the last named means 35 inoperative during the cycle when delivery is to take place.

HERMAN SOLTZ.
